UNITED STATES PATENT OFFICE.

SIMON FAIRMAN, OF BALTIMORE, MARYLAND.

CAR-BRAKE.

SPECIFICATION forming part of Letters Patent No. 321,428, dated July 7, 1885.

Application filed January 26, 1885. (No model.)

To all whom it may concern:

Be it known that I, SIMON FAIRMAN, a citizen of the United States, residing in Baltimore city, in the State of Maryland, have 5 invented a new and useful Improvement in Car-Brakes, of which the following is a specification.

My invention relates to car-brakes for steam-railways, and is so constructed as to be automatic in its action, all the cars in a train being under the control of the engineer in charge of the locomotive. I attain this object by the mechanism illustrated in the accompanying drawings, in which—

15 Figure 1 is a side view of certain parts of a car having the various parts of my invention displayed in their proper places; Fig. 2, a side view of one of the truck-sills. Fig. 3 is a face view of a revolving disk with ratchet-teeth and pawls. Fig. 4 is a side and edge view of a lever with its lower end forked. Fig. 5 is a longitudinal view of a car-axle with cam attached. Fig. 6 is an edge view of an oscillating arm.

25 Letter *b*, Figs. 1 and 2, is one of the truck-sills, to which is attached the loop *d*. This loop is semicircular, the king-bolt being the center of the circle.

30 Letter *l*, Figs. 3 and 1, is a revolving disk having ratchet-teeth on its upper face. It also has a sheave of small diameter, (indicated by letter *n*, Fig. 1.) To this sheave is fastened the brake-chain *o*.

35 Fig. 4 is a side and edge view of a lever, which has its fulcrum securely fastened to the truck-sill *a*. As seen in Fig. 1, its upper end is slotted, as represented by letter *t*. The lower end is forked, having a pin in each fork, (indicated by letter *v*.)

40 Letter *h*, Fig. 5, is a cam, which is attached to the inner axle of the truck.

45 Fig. 6 is an oscillating arm, having the king-bolt for its center of motion, and is represented by letter *g* in Fig. 1. The pawl *e*, Fig. 1, is pivoted to the front end of this arm, and its opposite end extends to the inner axle, and there engages the cam *h* and receives from it the oscillating motion which gives to the pawl *e* the same movement, and the pawl engaging the ratchet-teeth of the disk gives it a 50 revolving motion and winds the brake-chain

o around the sheave *n*, which gives effect to the brakes.

Letter *p*, Fig. 1, is a hand-lever having the pin *r*. This pin is long enough to engage a 55 similar lever attached to the next car, and when moved gives to it a turn in the same direction with like effect. This lever *p* is firmly attached to the actuating-bar *k*, which is properly fastened to the bottom of the car. 60 It extends through the entire length of the car. To this actuating-bar is also fastened the coupler *s* at a point nearly perpendicular over the loop *d*, Fig. 1. Its jaws inclose the upper end of the lever *i*, and has free action 65 in the slit *t*, so that when the hand-lever *p* is moved to the right or left it imparts a similar movement to the lever *i*. The pins *v*, impinging on the loop *d*, press it hard upon the free end of the pawls *f* and *e*, and disengage them 70 from the teeth of the disk and allow it to take a reverse movement, which unwinds the chain *o* from the sheave *n*, and thus relieves the brakes from operation. The opposite end of the chain *o* is attached to the usual means used 75 for braking purposes on steam-railways, which I do not broadly claim.

It may here be remarked that the free end of pawl *e* stands a little higher than that of pawl *f*, and by the pressure of the loop *d* thereon 80 it is first disengaged from the disk-teeth, while pawl *f* still holds its grip and keeps the disk in its position. When desirable to relieve pawl *f*, a further depression of the hand-lever *p* accomplishes it.

85 What I claim as my invention, and desire to secure by Letters Patent, is—

1. In a car-brake for steam-railways, the actuating-bar *k*, in combination with the hand-lever *p* and the coupler *s*, substantially as and for the purposes set forth.

2. The combination of the coupler *s*, the forked lever *i*, and the loop *d*, substantially as and for the purposes set forth.

3. The combination of the ratchet-disk *l* 9 and its sheave *n*, the oscillating arm *g*, and the cam *h*, all substantially as and for the purposes set forth.

SIMON FAIRMAN.
